(57) **CLAIM**

The ornamental design for a box joint alignment tool, as shown and described.

DESCRIPTION

FIG. 1 is an isometric view thereof;

FIG. 2 is a front view thereof;

FIG. 3 is a rear view thereof;

FIG. 4 is a side view thereof (from the right as seen in FIG. 1);

FIG. 5 is a side view thereof (from the left as seen in FIG. 1);

FIG. 6 is a top view thereof;

FIG. 7 is a bottom view thereof;

FIG. 8 is an isometric view of a second embodiment thereof;

FIG. 9 is a front view thereof;

FIG. 10 is a rear view thereof;

FIG. 11 is a side view thereof (from the right as seen in FIG. 8);

FIG. 12 is a side view thereof (from the left as seen in FIG. 8);

FIG. 13 is a top view thereof; and,

FIG. 14 is a bottom view thereof.

The broken lines in the drawings illustrate features that form no part of the claimed design.
